HOLDER FOR A TELEPHONE RECEIVER

Francis T. Itaya, 786 Sunshine Drive, Los Altos, Calif.

Filed May 7, 1962, Ser. No. 70,010

Term of patent 14 years

(Cl. D26—14)

Fig. 1

Fig. 3

Fig. 2

The portions shown in broken lines are for purposes of illustration only.

I claim:

The ornamental design for a holder for a telephone receiver, substantially as shown and described.
